UNITED STATES PATENT OFFICE.

CLIFFORD M. PAXTON, OF PIERMONT, NEW YORK, ASSIGNOR TO PAXTON CORPORATION OF AMERICA.

MARINE PROPULSION MEANS.

Application filed April 6, 1927. Serial No. 181,291.

My present invention relates to propulsion of boats by water jets, particularly those used in accordance with the principles set forth in my prior Patent No. 1,543,026, granted June 30, 1925. According to this method, the propulsion is by means of sheet jets from nozzles located on the entrance section of the boat in advance of and discharging through a region adjacent the under-water body of the ship, beneath where the maximum bow wave tends to pile up, when the ship is proceeding at speed. An important feature is "fitting" the jets to the hull of the ship, in accordance with the available pump pressure of the power plant and the predetermined operating speed. Important factors of the fitting of the jet are proper design of surface area of the jet relatively to the cross-section, in combination with proper outward angle of projection of the jet from the hull of the ship.

Suitable means for varying cross-section without substantial change of surface area of the jet may be afforded by a special construction of nozzle set forth in my application, Serial No. 176,600. My present invention may include all of the features of said prior application, together with practical means for adjusting the outward angle of the jet from within the ship while underway. The latter feature is of importance regardless of whether or not the thickness of the jet is adjustable in accordance with said application.

The above and other features of my invention will be more evident from the following description in connection with the accompanying drawings, in which—

Fig. 1 is a sectional view transversely of the jet nozzle;

Fig. 2 is a side elevation;

Fig. 3 is a detailed view of the nozzle element; and

Fig. 4 is a top plan view of the complete device.

In Fig. 1, the plate 1 is supposed to be the bow plating of the hull of the ship, full showing of which is not essential to an understanding of my present invention. The water for the jets is supplied through a header 2, which is formed with a flange 3 fitting against the face of the hull plate 1, which has an opening 4 cut therethrough corresponding to the interior conduit portion of the header. The corresponding exterior conduit member, 5, forming a continuation of

the passage 2, is also provided with a flange 6 fitting against the exterior of the hull. The flanges are rigidly secured to each other and to the hull plate as by rivets 7, 7, and the rearwardly directed portion of the header 5, is formed with curved bearing surfaces 8, 8, which are preferably segments of a tapering cone within which may be endwise inserted a cone plug 9, an elevation of which is shown in Fig. 3. This cone plug is formed with passages transverse to its axis, which are shaped as jet nozzles, the horizontal section being clearly shown in Fig. 1 and the outlet orifice in Fig. 3.

As shown in Fig. 2, the outboard casting 5 is formed with a removable head 11, of proper size to cover the large end of the nozzle cone, the far end of the cone being retained by an integral head 12. Preferably, the nozzle member is provided with a shaft 13 projecting from its small end. This projects through the head member 12 and is secured by lock nuts 14, 14, which may be secured by pin 15, indicated in Fig. 3.

The larger end of the nozzle cone also has an axial shaft member 16, projecting through the head 11 and having thereon a worm wheel 17 non-rotatably secured as by key 18. The worm wheel is rotated to rotate the plug to required position of adjustment by worm 18 on a shaft 19 secured in suitable bearing 20 on the casting 11 and extending through the plate 1 to the interior of the vessel and formed at the end 19^a for engagement by handwheel, wrench or other device suitable for rotating it to adjust the angle of the nozzle member 9. Suitable bearing and packing means may be provided in the form of members 20 and 22, the latter being provided within the ship with a packing gland 23, closed by cup 24.

While it is evident that the jet cross-section shown in Fig. 1 could extend the entire length of the rotary nozzle element in a single sheet, I prefer to divide the space lengthwise into three nozzles, 25, 26, 27, separated by short lengths of metal integral with the plug.

While it is not essential to the adjustability feature of my present invention, the effective widths of the jet orifices may be made adjustable after the manner set forth in my prior application, that is, by having interior plates or liners 28 that are capable of adjustment inward and outward by set screws 29, 110

provided with lock nuts 30. To permit such movement, the liners 28 are preferably of spring bronze shaped to fit the curvature of the interior surfaces of the nozzle and having their nozzle ends free and their remote portions anchored to the plug, preferably rigidly as by screws 31, 31. Preferably, the spring set of these liners is such as to cause them to normally lie flat against the nozzle surface and they are further forced against such surfaces by the jet pressure when in operation. To effect desired narrowing of the slot outlet of the nozzle, to reduce the cross-section of the jet without substantial reduction of its surface area, or for the purpose of increasing velocity by varying the back pressure or throttle effect of the nozzle, the set screws are simply screwed inward a desired distance. Preferably, the arrangement is such that the rotary adjustment by means of worm 18 will be sufficient to bring the screws 30 clear of the housing passage.

By my above invention I have provided means whereby the jets may be fitted to the hull of the vessel to suit varying conditions or contingencies such as partial failure of pumps or motive power or varying speed of ship due to varying full-load and no-load conditions and for low speed operation under special conditions of traffic or storm.

I claim:

1. A marine vessel and water jet propelling means therefor including a conduit for supply of water under pressure and an exterior submerged nozzle member therefor in the form of a circular elongated member rotatably mounted and having its axis extending downward along the hull and having an outlet passage extending transversely of said axis, the outlet end thereof being a slot-like orifice extending lengthwise of said axis, in combination with means controlled from within the ship for rotating it.

2. A marine vessel and water jet propelling means therefor, including a conduit for supply of water under pressure and an exterior submerged nozzle member therefor in the form of a circular member rotatably mounted, means controlled from within the ship for rotating it, and means for varying the area of the nozzle outlet.

3. A marine vessel and water jet propelling means therefor, including a conduit for sup-

ply of water under pressure and an exterior submerged nozzle member therefor in the form of an elongated member mounted for rotation on an axis extending downward along the hull and having outlet passages extending transversely to said axis each having a slot-like orifice extending lengthwise of said axis, in combination with means extending within the ship for rotating said nozzle member about said axis.

4. A marine vessel and water jet propelling means therefor, including a conduit for supply of water under pressure and an exterior submerged nozzle member therefor in the form of an elongated member mounted for rotation on an axis extending downward along the hull and having outlet passages extending transversely to said axis, in combination with means extending within the ship for rotating said nozzle member about said axis, and means for varying the area of the nozzle outlet.

5. A marine vessel and water jet propelling means therefor, including a conduit for supply of water under pressure and an exterior submerged nozzle member therefor, in the form of a rotatably mounted truncated cone having its axial length much greater than its diameter and formed with transverse conduit passages having elongated orifices.

6. A marine vessel and water jet propelling means therefor, including a conduit for supply of water under pressure and an exterior submerged nozzle member therefor, in the form of a rotatably mounted truncated cone having its axial length much greater than its diameter and formed with transverse conduit passages having elongated orifices parallel with said axis.

7. A marine vessel and water jet propelling means therefor, including a conduit for supply of water under pressure and an exterior submerged nozzle member therefor, in the form of a rotatably mounted truncated cone having its axial length much greater than its diameter and formed with transverse conduit passages having elongated orifices parallel with said axis, and means for varying the area of the nozzle outlet.

Signed at New York in the county of New York, and State of New York, this fifth day of April, A. D. 1927.

CLIFFORD M. PAXTON.
